ington, N. J., a corporation of New Jersey

Application September 21, 1948, Serial No. 50,255

7 Claims. (Cl. 1—25)

1

This invention relates to fastening inserting machines, and is particularly concerned with improvements in fastening inserting machines of the type in which a strand of fastening material, such as a metal wire, is inserted into the work parts to be united, whereupon a fastening is formed from the inserted leading end portion of the strand.

It is an object of the invention generally to improve upon machines of the above-described type and more specifically to provide an improved fastening inserting machine of the above-mentioned type which is adapted to insert a fastening into the work parts in such a manner that the fastening does not penetrate the full thickness of the combined work parts but becomes anchored within these parts.

In accordance with a feature of the invention the illustrated machine is provided with a reciprocating, positively acting wire clamp which, during its active stroke, holds the wire firmly gripped and advances it a predetermined distance through and out of the machine, there being also provided a deflector against which the positively fed wire is caused to impinge before entering the work with the result that the wire follows a curved path within the work without penetrating entirely through the work. A combined shearing, curling and clenching member which cooperates with the deflector then is rendered active first to shear off the inserted leading end portion of the wire strand a certain distance above the work while progressively forming a curled point and then to clench the trailing end of that portion over into the work, thus forming a staple-like fastening, both ends of which are firmly lodged within the substance of the combined work parts united by the fastening.

These and other features of the invention will now be described in detail in connection with the accompanying drawings and will be pointed out in the appended claims.

In the drawings,

Fig. 1 is a view in right-hand side elevation of the main operating instrumentalities, as well as their actuating members, of a fastening inserting machine in which the present invention is embodied, the parts being in the positions assumed prior to the inflation of its operation;

Fig. 2 is a detail view of a wire shearing, curling and clenching member in the position it assumes after the completion of its operative stroke, a fastening having been formed and inserted into the work;

Fig. 3 is a view similar to Fig. 1 with the ma-

2

chine parts assuming their positions at the completion of the wire feeding stroke;

Fig. 4 is a front elevation of the main operating instrumentalities of the machine in the normal 5 inoperative position, with certain parts removed or broken away;

Fig. 5 is a front elevation of the parts shown in the lower portion of Fig. 4, with these parts assuming their positions at the completion of 10 wire strand shearing;

Fig. 6 is a sectional view in front elevation of a wire clamp which is part of the wire feeding mechanism;

Fig. 7 is a plan view of the wire feeding mechanism;

Fig. 8 is a plan view of the machine parts illustrated in Fig. 1;

Fig. 9 is a view of the inside face of a side plate 15 of the machine throat from which the wire passes into the work;

Fig. 10 is a rear elevation showing the position of the wire deflecting pusher and the combined shearing, curling and clenching instrumentalities just prior to their operation upon the wire strand;

Fig. 11 is a perspective view on an enlarged 20 scale of the wire deflecting and combined shearing, curling and clenching instrumentalities showing the manner in which the wire is simultaneously sheared and curled; and

Figs. 12, 13, 14 and 15 are left-hand side elevations, partly in cross section, each respectively showing the successive stages and manner in which the protruding portion of the wire strand is progressively and simultaneously sheared and 25 curled, then finally clenched over and downward into the work.

The illustrated fastening inserting machine, as stated above, is adapted to insert a wire strand into work parts to be united and to cause the 30 wire strand to follow a curved path within the work parts without penetrating their full thickness, then to sever the inserted leading end portion from the strand at a distance above the work while simultaneously forming a downwardly 35 curled point and then to clench it over into the work. By way of illustration, the machine is shown herein as adapted to secure, by means of a staple-like fastening A (Fig. 2) produced by the machine, the overlasted marginal portion of a shoe upper B to an insole C. The wire strand from which the fastening A is formed is indicated at D in Figs. 1, 3 to 7, and 9 to 11. This wire strand is preferably coiled up on a reel (not shown) which, as usual, is rotatably mounted on 40 the machine and from which the wire strand D

is guided into and through the machine to be processed in the manner described. Preferably the wire strand is of rectangular cross-section. Upon entry into the machine proper the wire is engaged by a wire feeding mechanism by which it is passed along and out of a wire guide to impinge a deflector before entering the work in a curved path. A combined shearing, point curling and clenching member then severs the leading end portion of the wire strand to form the fastening A, as already indicated.

The main elements or mechanisms of the machine which have been just briefly introduced are directly or indirectly supported on the machine frame 10 (Figs. 1, 4 and 8) which preferably is a hollow head mounted on a column. A gage 12 (Figs. 1 to 3) adjustably secured to the machine frame determines, by engagement with the work, the horizontal position of the manually supported work in the machine.

The wire guide briefly mentioned above comprises primarily two bars 14, 16 (Fig. 6) which are held in mutual abutting position and extend heightwise of the machine. The abutting faces of the bars 14 and 16 are milled out, as best shown in Fig. 7, to provide a guideway of rectangular cross-section adapted to contain and guide the wire strand D. The two bars 14, 16 are mounted in an assembly comprising vertically spaced rear blocks 18, 20 (Figs. 1 and 3), the blocks being connected by a bar 22 to form an integral unit. In abutting relation with the front faces of the blocks 18, 20 are vertically spaced front blocks 24, 26 also connected by a bar 28 to form an integral unit. The abutting upper blocks 18 and 24, as well as the abutting lower blocks 20 and 26, are secured by screws, indicated at 30 and 32 in Figs. 1 and 4, to a large front plate 34 which in turn is bolted to the machine frame 10.

A wire intake member 36 (Figs. 1, 3 and 8) in the form of a block is secured on top of the block 18 and held within a rabbeted recess in the block 24. This wire intake member 36 contains a conventional wire brake designed to prevent retrograde movement of the wire strand D.

The above-mentioned wire guiding passage provided between the bars 14 and 16 is continued below the blocks 20 and 26, as will be described. The block 20 has integral therewith a lower bar-like extension 38 (Figs. 1, 3 and 4) and secured to that extension 38 is a main throat block 40. The block 40 is of rectangular cross-section and its narrow sides are facing front and back. The right-hand side of the block 40, as seen from the front of the machine, is plane or smooth and attached to it by screws is a deflector plate 42 (Fig. 4) which is detached in Figs. 1 and 3 and is separately shown in Figs. 9 and 11. The inside face or left-hand face of the deflector plate 42 (as seen from the front of the machine) is provided with an insert member 44, the exposed surface of which lies in the same plane as the inside face of the deflector plate 42. The insert member 44 is slightly spaced along the right-hand edge thereof, as seen in Figs. 9 and 11, from the adjacent portion of the deflector plate 42, thus forming a wire guiding passage 46. The upper end of the wire guiding passage is in alignment with the lower portion of the wire guiding passage provided between the bars 14 and 16. The lower right-hand portion 48 of the insert member 44 is rounded and the adjacent portion of the deflector plate is correspondingly rounded while maintaining the

same spaced relation therewith, thus causing the wire guiding passage 46 to curve toward the left of Figs. 9 and 11. As the wire leaves the throat it is caused to curve in a reverse direction by impingement upon a deflector portion 50 of the insert member 44. The deflector portion 50 progressively curves the wire as it is being fed out of the passage 46, thus causing the leading end portion of the wire strand to enter the work in a curved path without penetrating the full thickness of the work. The work is being held against the lower faces of the block 40 and the plate 42, which two members constitute the throat of the machine.

For the purpose of intermittently feeding the wire strand through the machine there is provided wire feeding mechanism comprising a vertically reciprocating wire clamp in the form of a chuck which is adapted intermittently to engage the wire to grip it and then to move the wire down while maintaining its gripping engagement therewith. The chuck is illustrated best in the sectional view of Fig. 6. It comprises two spaced parallel side plates 52 provided with forwardly and rearwardly extending guide flanges 54 (see Fig. 7). These guide flanges engage and run along opposite side faces of the bars 22 and 28, thereby guiding the entire chuck during its vertical reciprocation. The lower portions of the two side plates 52 are connected together by a spacing member or web 56 which is pinned to both plates 52. A top plate 58 is secured to the top of the side plates 52. There are provided two bores 60 in the web 56 in which are seated springs 62. Inside the casing made up by the side plates 52 and the web 56 there are provided two opposite wire gripping members 64 which have wire engaging portions 66 that are V-shaped in cross-section. The portions 66 of the gripping member 64 are adapted to enter V-shaped recesses 68 (Fig. 7) provided in opposite faces of the bars 14, 16, thereby engaging the wire strand D between them. The wire gripping members 64 which are engaged by the upper ends of the springs 62 are provided with inclined outer faces 70 (Fig. 6) which are parallel to inclined inner faces 72 of wedge members 74. The faces 70 and 72 are spaced apart a predetermined distance and in this space are located balls 76. Integral with the outer sides of the wedge members 74 are pins 78 which extend through holes provided in the side plates 52 into pivot blocks 80 (Figs. 4 and 7). The blocks 80 are mounted in guideways 82 provided at the insides of the tines of the forked front end 84 of the horizontal arm of a bell crank lever 86 (Figs. 1 and 3). The bell crank lever 86 is mounted for oscillating movement about a fixed shaft 88 secured in the machine frame 10. It will be noted that the springs 62 seated in the web 56 tend to move the wire gripping members 64 upwardly to loosen their grip on the wire strand D. Thus on upward swinging movement of the just-mentioned horizontal arm of the bell crank lever 86 the two gripping members 64, under the influence of the springs 62, slide idly along the wire strand D until the horizontal arm of the bell crank lever 86 has reached the upper limit of its travel. On downward movement (counterclockwise in Fig. 1) of that arm which is its operative stroke, the wedge members 74, being positively connected to the bell crank lever 86, exert a strong wedging action on the wire gripping members 64 displacing them laterally toward the wire D with the result that these

members firmly grip the wire between them. During and as a result of the downward movement of the entire chuck, they then advance the wire strand, the strand passing along the guideway provided between the bars 14 and 16, as well as passing through the guideway 46 of the throat of the machine. Having reached the lower end of its operative stroke, the horizontal arm of the bell crank lever 86 again begins its upward travel with the result that under the action of the springs 62 the gripping members 64 again slip idly along the wire strand D preparatory to another wire feeding movement. Fig. 1 illustrates the bell crank lever 86 in its uppermost position prior to the initiation of its operative stroke and Fig. 3 illustrates the same bell crank lever at the end of its operative stroke and in its lowermost position.

The wire strand in being given a downward movement by the just-described chuck mechanism is passed along, as has been mentioned, the wire guiding passage 46 of the throat member, is curved by the portion 48 of the insert member 44, then is caused to impinge upon the deflector portion 50 to be curved in the opposite direction and to enter the work in a curved path.

Since it is desirable to sever the wire strand by means moving in the direction of wire feed but intersecting the wire strand at an acute angle, the illustrated machine is provided with special means adapted to bend the leading end portion of the wire strand contained in the lower end of the throat out of the forwardly and rearwardly extending vertical plane of its normal path of movement. Accordingly, the wire strand may be sheared by a cut executed in a vertical plane, it being understood that the lateral bending or deflection of a portion of the wire strand causes that portion to intersect the vertical plane of the shearing cut. To this end there is mounted in a recess 90 (Figs. 1 to 3) provided in the lower portion of the extension 38 of the block 20 a pusher 92. The pusher 92 is movable in the general direction of work feed, i. e. in the plane of Fig. 4 and is secured on the downwardly curved arm of a small two-armed lever 94 which is mounted for pivotal movement on a pivot pin 96 secured in the extension 38. In its normal inoperative position illustrated in Fig. 4, the pusher 92 is located adjacent to, but out of contact with, the wire strand D and it is only on account of a rocking movement imparted to the lever 94 that the pusher 92 is caused to engage the wire strand D and to bend it across the vertical plane of the shearing cut. To operate the lever 94 and pusher 92 the left-hand end (as viewed in Fig. 4) of the lever 94 is pivotally connected by a ball-and-socket linkage 98 (Figs. 1, 3 and 4) to a two-armed lever 100 which is mounted for rocking movement upon a fixed shaft 102 secured in the machine frame.

The main throat block 40 is provided with a recess 104 (Figs. 1 and 3) in which is mounted for rocking movement about a horizontal pivot pin 106 a combined wire shearing and curling member 108 (Figs. 1 to 4) the lower edge of which is the cutting edge. As already indicated, the member 108 is movable in a vertical plane, this movement taking place about the pivot pin 106 and during its downward stroke the shearing edge of the member is adapted to sever the leading end portion of the wire strand from the strand while the flat bottom surface of the member progressively pushes or curls the just-sheared portions downward and finally continued move-

ment of the member clenches the curled trailing end, of that portion which protrudes from the work, over and into the work thus forming the fastening A illustrated in Fig. 2. As graphically illustrated in Figs. 12 through 15, the shearing and curling of the wire strand and the clenching of the fastening all take place in one continuous motion of the combined shearing, curling and clenching member 108. In order to actuate the shearing and clenching member 108, its right-hand end, as viewed in Figs. 1 and 3, is pivotally connected by means of a link 110 to a two-armed lever 112 mounted for rocking movement on the fixed shaft 102.

The driving mechanisms for actuating, in time relation, the above-described wire feeding mechanism, the pusher 92 and the shearing and clenching member 108, will now be described. Referring first to the driving mechanism for operating the wire feeding mechanism, it is to be noted that this mechanism derives its power from a loaded torsion spring 114 (Figs. 1 and 8) which is mounted on a fixed shaft 116, the shaft being secured in the machine frame 10. One end of the spring 114 abuts a pin 118 projecting laterally from a disk 120. The disk 120 is rotatably mounted on the shaft 116 and is held in adjusted position by a pin 122 which engages one of a series of semi-circular recesses provided in the periphery of the disk 120. The pin 122 extends through one of a series of adjustment holes 124 provided in a fixed plate 126 secured to the machine frame 10 and located adjacent to the rotatable disk 120. Adjustment of the disk 120 varies the tension of the spring 114. The other end of the spring 114 abuts the rear face (right-hand face in Figs. 1 and 3) of the vertical arm of the bell crank lever 86. It will be noted, therefore, that the force of the loaded spring when permitted to act on the bell crank lever 86 swings the bell crank lever in a counter-clockwise direction, as viewed in Fig. 1, to impart to the chuck a wire feeding motion.

To tension the spring 114 and to hold the bell crank lever 86 cocked against the force of the tensioned spring 114, there is provided special mechanism, illustrated best in Figs. 1 and 3, which will now be described. Secured in the upper portion of the vertical arm of the bell crank lever 86 is a lateral pin 128 which extends into a slot 130 provided in the enlarged forward end portion of a rod 132. The rod 132 is pivotally secured at its rear end by a pin 134 to a fork member 136 which is adapted to rock on a fixed shaft 138 secured in the machine frame. To rock the fork member 136, the machine is provided with a power-operated main drive shaft 140 on which is secured a cam disk 142. The cam disk 142 engages the inner faces of the tines of the fork member 136 and causes the fork member 136 to be oscillated about the shaft 138, thereby reciprocating the rod 132. Movement of the rod 132 toward the right from the position illustrated in Fig. 3 tensions the spring 114 and cocks the bell crank lever 86, that is to say, swings the bell crank lever in a clockwise direction back into its initial position, illustrated in Fig. 1. The spring 114 is held tensioned or loaded and the bell crank lever 86 is held cocked by a latch 144 which engages the upper end of the vertical arm of the bell crank lever 86. The latch 144 is rotatably mounted on a fixed shaft 146 secured in a bracket 148 of the machine frame 10. A spring 150, one end of which is mounted in a socket provided in the bracket 148 and the other end of which is

mounted in an alined socket provided in the top face of the latch 144, tends to swing the latch into its latching position, illustrated in Fig. 1. The latch 144 has a tailpiece 152 which, at a predetermined point during a machine cycle, is operated to lift the latch and to release the bell crank lever 86 to the force of the loaded spring 114. To lift the latch 144 there is provided a latch tripping member 154 secured on the rod 132. In the position of the machine parts, as illustrated in Fig. 1, it will be seen that on movement of the rod 132 toward the left of that figure the tripping member 154 is caused to strike against the tailpiece 152 to swing the latch 144 in a clockwise direction out of engagement with the bell crank lever 86, thus releasing the bell crank lever to the force of the spring 114 and imparting a wire feeding motion to the chuck. It will be noted also that on movement of the rod 132 toward the left of Fig. 1, there is a lost motion between the lateral pin 128 of the bell crank lever 86 and the forward end of the rod 132 due to the provision of the slot 130 so that upon release of the bell crank lever 86 it may be rapidly rotated by the loaded spring 114 with the lateral pin 128 traveling the length of the slot 130 to the forward end thereof, as shown in Fig. 3. Return movement of the rod 132 toward the right of Fig. 3 and from the position illustrated therein again cocks the bell crank lever 86 and loads the spring 114. At the same time the trip member 154 is removed from the tailpiece 152 of the latch 144 so that the latter, under the influence of the spring 155, may again engage the upper end of the vertical arm of the bell crank lever 86 as soon as that arm arrives beneath the hooked forward end of the latch 144.

It will be noted in Figs. 1 and 3 that the bell crank lever 86 has a rearwardly extending tailpiece 156 which, on rotation of the bell crank lever 86 in a counterclockwise direction by the spring 114, is caused, toward the end of that rotary motion of the bell crank lever 86, to strike against the tailpiece 158 of an arm 160 pivotally secured on a shaft 162 mounted in the machine frame. The rearward end of the arm 160 is pivotally connected to a link 164 which extends through a tailpiece 166 of a latch 168 similar to the latch 144 and also mounted adjacent to the latch 144 to rock on the shaft 146. The link 164 is freely movable through an aperture in the tailpiece 166 and carries at its upper end a nut and a lock nut, the nut being normally seated upon the top face of the tailpiece 166. The latch 168 also is spring biased in the same way as the latch 144 and in its operative position the latch 168 holds cocked a two-armed lever 170 which is mounted for rocking movement on the shaft 88. The lower end of the downwardly extending arm of the lever 170 carries two rollers 172 pivotally mounted on opposite sides thereof. One of the rollers 172 engages a cam track 174 provided in the previously mentioned lever 100 and the other roller 172 engages a cam track 176 provided in the previously mentioned lever 112. The two cam tracks 174 and 176 have different configurations with the result that on swinging movement of the lever 170 in a counterclockwise direction (as seen in Fig. 1), movements are imparted to the levers 100 and 112 in a staggered time relation.

The just-mentioned swinging movement of the lever 170 in a counterclockwise direction to actuate the levers 100 and 112 and thereby to actuate the pusher 92 and the combined shearing and clenching member 108 is derived from a

loaded torsion spring 178 (Fig. 8) which also is mounted on the shaft 116. One end of the torsion spring 178 engages the rear face of the upwardly extending arm of the lever 170 and the other end of the spring lies against a pin 180 which, in a fashion similar to that described in connection with the spring 114, is mounted on a disk 182 rotatable on the shaft 116 and held in adjusted position by a pin 184 extending through one of a series of positioning holes provided in a fixed plate 186 into one of a series of peripheral recesses in the disk 182.

To tension the spring 178 and to cock the lever 170, there is provided a rod 188 which is similar to the rod 132 and also has at its forward end a slot (not shown) similar to the slot 130, the slot of the rod 188 being engaged by a lateral pin (not shown) provided on the upper arm of the lever 170. The rear end of the rod 188 is pivotally connected by a pin 190 (Fig. 8) to a fork member 192 corresponding to the fork member 136 and also mounted for rocking movement about the shaft 138. A cam 194 on the main shaft 140 engages the tines of the fork member 192 and on rotation of the main shaft 140 thus causes oscillation of the fork member 192 and reciprocation of the rod 188. When the rod 188 is moved to its right-hand position, as viewed in Fig. 1, the latch 168 is caused to engage the upper arm of the lever 170 so as to hold the spring 178 loaded and the lever 170 cocked in readiness for the tailpiece 156 to strike against the tailpiece 158, thereby to lift the latch 168 and to release the lever 170 to the force of the loaded spring 178.

The operation of the machine will now be briefly summarized. Considering the initial position of the machine parts, as illustrated in Fig. 1, it will be realized that on initiation of the rotation of the main shaft 140 which may be conventionally effected by means of a treadle controlled clutch, forward movement, that is movement toward the left of Fig. 1, is imparted to the rods 132, 188, the forward ends of the rods moving idly with relation to the machine elements with which they are connected due to the provision of the slots in these forward ends. As soon as the tripping member 154 strikes against the tailpiece 152 of the latch 144, the latch 144 is raised to release the bell crank lever 86 to the force of the loaded spring 114, thereby imparting a wire feeding motion to the chuck, as previously described. Toward the end of the swinging movement of the bell crank lever 86 in a counterclockwise direction, the tailpiece 156 strikes against the tailpiece 158 with the result that the latch 168 is lifted so as to release the cocked lever 170 to the force of the loaded spring 178 and to operate in time relation the pusher 92 and the combined shearing and clenching member 108. The configurations of the cam tracks 174, 176 in the rearward arms of the levers 100, 112 are such that the pusher 92 is first operated to deflect the already fed wire strand D into the vertical path of movement of the shearing member 108 (as shown in Figs. 10 and 11), after which the shearing member 108 is operated to move in the direction of wire feed and to shear off the inserted leading end portion of the fed wire strand at a distance above the work, the cutting edge of the shearing member 108 intersecting the wire strand at an acute angle (Fig. 10), thereby providing a fine point which, due to the continued operation of the shearing member 108 (Figs. 12 to 15), then is curled over and clenched into the work to produce the completed

fastening illustrated in Fig. 2. The machine parts now assume the positions illustrated in Fig. 3 whence they are returned to their initial position by the rearward motions of the rods 132, 188 under the control of the cams 142 and 194. This concludes the machine cycle.

Having thus described my invention, what I claim as new and desire to secure by Letters Patent of the United States is:

1. In a fastening inserting machine, a guiding passage, means for intermittently feeding a strand of fastening material through said passage and into a work piece presented to the machine, a combined shearing, curling and clenching member movably mounted as to be operable in a path adjacently parallel to said passage, said member having a shearing edge inclined at an acute angle to the direction of the strand as it emerges from out the guide passage and having a lower surface portion facing the work piece and extending laterally from the shearing edge, means operable upon completion of the feeding movement of the strand into the work piece for bending the strand laterally across the path of said member at an acute angle, and means actuated upon completion of said bending for operating said member in one continuous motion first to shear off the strand at a distance above the work surface while progressively curling the sheared portion of the strand beneath the surface of the member and toward the surface of the work and then to clench the curl of the completely sheared trailing end portion of the strand downwardly and re-entrantly into the work piece.

2. In a fastening inserting machine, a guiding passage, means for intermittently feeding a strand of fastening material through said passage and into a work piece presented to the machine, a deflector adjacent said surface against which deflector the strand impinges before entering the work with the result that the strand follows a curved path within the work without penetrating entirely through the work, a shearing member movably mounted as to be operable in a path adjacently parallel to said passage, means operable upon completion of the feeding movement of the strand into the work piece to engage the strand transversely between said deflector and passage and to bend the strand laterally across the path of said member so that the strand may be intersected by the shearing member, and means actuated upon completion of said bending for operating said member to shear off the strand at a distance above the work surface.

3. In a fastening inserting machine, a guiding passage, means for intermittently feeding a strand of fastening material through said passage and into a work piece presented to the machine, a deflector adjacent said surface against which deflector the strand impinges before entering the work with the result that the strand follows a curved path within the work without penetrating entirely through the work, a combined shearing, curling and clenching member movably mounted as to be operable in a path adjacently parallel to said passage, said member having a shearing edge inclined at an acute angle to the direction of the strand as it emerges from out the guide passage and having a lower surface portion facing the work piece and extending laterally from the shearing edge, means operable upon completion of the feeding movement of the strand into the work piece to engage the

strand transversely between said deflector and passage and to bend the strand laterally across the path of said member so that the strand may be intersected by the shearing member at an acute angle, and means actuated upon completion of said bending for operating said member in one continuous motion first to shear off the strand at a distance above the work surface while progressively curling the sheared portions of the strand beneath the surface of the member and toward the surface of the work and then to clench the curl of the completely sheared trailing end portion of the strand downwardly and re-entrantly into the work piece.

15 4. In a fastening inserting machine, a guiding passage, means for intermittently feeding a strand of fastening material through said passage and into a work piece presented to the machine, means associated with said passage for curving the strand in one direction, a deflector adjacent said work surface against which deflector the strand impinges as to bend the strand in the opposite direction to cause the strand to enter the work in a curved path and to follow a 20 curved path within the work without penetrating its full thickness, a shearing member movably mounted as to be operable in a path adjacently parallel to said passage, means operable upon completion of the feeding movement of the strand 25 into the work piece to engage the strand transversely between said deflector and passage and to bend the strand laterally across the path of said member so that the strand may be intersected by the shearing member, and means actuated upon completion of said bending for operating said member to shear off the strand at a 30 distance above the work surface.

5. In a fastening inserting machine, a guiding passage, means for intermittently feeding a 35 strand of fastening material through said passage and into a work piece presented to the machine, a shearing member movably mounted as to be operable in a path adjacently parallel to said passage, means operable upon completion of the feeding movement of the strand into the work 40 piece for bending the strand laterally across the path of said member so that the strand may be intersected by the shearing member, and means actuated upon completion of said bending for operating said member to shear off the bent portion 45 of the strand at a distance above the work surface.

6. In a fastening inserting machine, a strand feeding clamp operated in sequence to engage a 50 strand, advance the strand through the machine and insert its leading end portion into a work piece presented to the machine, means for actuating the clamp, a pivotally movable combined shearing, curling and clenching member adjacent the work surface, a guiding passage extending from the feeding clamp to the member for directing the strand as it is being fed towards the work through a plane contiguously adjacent to the path of said member, a deflector against which the strand is progressively directed by said passage during the feeding movement to impart a curve to the leading end portion of the strand directed downwardly toward the work with the result that the strand follows a curved path 55 within the work without penetrating entirely through the work, a pusher element arranged for movement upon completion of the strand feeding for contacting and bending said end portion out of the plane of its normal path of movement and into the path of movement of the combined 60 70 75

shearing, curling and clenching member, said member having a shearing edge and a lower surface portion facing the work piece and extending laterally from the shearing edge, and means actuated upon bending of the end portion of the strand for operating said member to cause said edge to engage the bent strand portion at an acute angle to progressively sever the strand while simultaneously directing the just-severed portions to beneath the surface portion of the member so that continued operative movement of the member curls the completely severed end downward toward the surface of the work and then clenches the end into the work piece.

7. In a fastening inserting machine, a strand guiding passage, means for intermittently feeding a strand of fastening material through said passage and into a work piece presented to the machine, a movable strand shearing member mounted as to be operable in a path adjacently parallel to said guiding passage, a strand pusher operable upon completion of the feeding move-

ment of the strand to engage the strand transversely as the strand emerges from said passage and to push it laterally across the path of said member, means for operating the feeding means to insert the leading end of the strand into the work piece, and means actuated upon completion of the feeding movement of the strand for operating first the strand pusher and then said member to shear off the strand at a distance above the work surface.
